(57) **CLAIM**

The ornamental design for a retail packaging for consumable products, as shown and described.

DESCRIPTION

FIG. 1 is a perspective view of the retail packaging for consumable products showing our new design;

FIG. 2 is a front view thereof;

FIG. 3 is a rear view thereof;

FIG. 4 is a side view thereof;

FIG. 5 is another side view thereof;

FIG. 6 is a top perspective view in an opened configuration thereof;

FIG. 7 is a bottom view thereof;

FIG. 8 is a top, front and side perspective view in an open configuration thereof; and,

FIG. 9 is a perspective view thereof wherein consumable products are shown through the window of the packaging. The broken line showing or portions of the claimed design is included for the purpose of illustrating environmental structure and forms no part of the claimed design.
